CARD FOR DIRECT AND SEQUENCE
SORTING

Albert A. Rembold, San Francisco, Calif.

Application February 15, 1944, Serial No. 522,440

3 Claims. (Cl. 129—16.1)

1

This invention relates to cards, sheets, etc. as are used in keeping records.

Heretofore two sorting methods have been used, the most common of which has been the method for "sequence" sorting of cards. The other method is called "direct" or "selective" sorting.

Sequence sorting involves successive removal of undesired cards from a stack leaving the desired cards in the desired order. This method is mainly for arranging cards in proper order in a stack.

"Direct" or "selective" sorting is where the desired card or cards are directly removed from a stack irrespective of the order of the cards in the stack.

Typical examples of structures heretofore employed, in the order of their development, are found in United States Letters Patents to Perkins, No. 1,544,172, June 30, 1925, and 1,739,087, December 10, 1929; Nevin, No. 2,289,380, July 14, 1942, and No. 2,213,607, September 3, 1940. In each of these patents the acknowledged end has been to produce a combination of physical structure and printing that will increase the capacity of the cards or that will permit a reduction in the size of the card without reducing its capacity or manipulative possibilities. If the structure in a marginal portion of, say about two inches in length along one edge of a card will permit the sequence sorting of the same number of classifications as was heretofore required in a wider marginal portion that is almost five inches in length, there is a great saving in material if the smaller sized cards are used, or the capacity of the larger card for classifications is more than doubled.

With my invention I have not only provided a structure that increases the classification capacity of cards, but have at the same time provided a structure for both sequence and direct sorting, a result heretofore never accomplished without utilizing more than double the length of marginal space required by me. Furthermore common structure is used by me for accomplishing both direct and sequence sorting.

The principal object of this invention is to provide a structure in which coded perforations in fields along one edge of a card are respectively notched to form patterns of notches in said edge

2

that provide for direct or sequence sorting of the cards as may be desired in the same or substantially less space than heretofore would be required to accomplish the same general result.

5 Other objects and advantages will be seen in the drawing and specification annexed hereto.

In the drawing:

Fig. 1 is illustrative of my invention in which two rows of perforations are adjacent one edge of a card and which perforations are divided into numerical fields or groups of eight with one smaller group, said fields or groups being separated by printed lines.

Fig. 2 is a fragmentary view of separate fields 10 on a single card respectively notched out to show patterns corresponding to the numbers 3, 5, 6, 8 and 9 while Fig. 3 shows the patterns of notches, perforations and numbers corresponding to the numbers 1, 4, 2 and 1.

20 Fig. 4 is a view of a pattern of notches, indicia and perforations in the edge of the card for direct or selective sorting of a card identified by the number 90,731, and Fig. 5 shows a pattern for direct or selective sorting of card No. 27,614.

25 In actual practice the length of the pair of rows of perforations shown in Fig. 1 is preferably about 3.7 inches, and the diameter of each perforation may be about .075 inch. The said rows including the numerals may be contained in a marginal portion about .4 inch wide. Thus a card about 7.5 inches in length would contain double the number of perforations shown in Fig. 1 along one edge only. Or consecutively numbered classifications from one to ten million could be sorted by 30 the direct or sequence sorting method in fields contained in one narrow longitudinal margin of a standard card only five inches in length.

The card 1 of Fig. 1 may be of any desired 40 length and width and is provided along one or more of its edges with a plurality of rows of perforations 2. These rows are parallel with the edge or respective edges along which they extend. In Fig. 1 one pair of such rows is shown, the first row being adjacent said edge and the second row being adjacent said first row but spaced therefrom a distance about the diameter of a perforation 2, or less, said perforations 2 being of uniform diameter.

45 The perforations of the second row are respec-

tively in alignment with the perforations of the first row in direction at right angles to the edge 3 along which said rows extend.

For numerical classifications the rows are divided transversely thereof into fields by printed lines 4. From right to left in Fig. 1 these fields are indicated at 5, 6, 7, 8 and 9, and in each field are four perforations in each of the two rows, or four pairs of adjacent perforations, each pair being an opening from each of the two rows.

The field 5 may refer to "units" below ten, field 6 to "tens," field 7 to "hundreds," field 8 to "thousands," and field 9 to "tens of thousands," and said fields may respectively be so designated as shown in Fig. 1.

The four pairs of openings in each field from left to right may be successively identified by numerals 1, 4, 2, 1, or 6, 3, 2, 1, although the former numerals are preferable.

It is pertinent to note that each perforation of a corresponding pair in alignment in each field in direction at right angles to the edge of the card adjacent thereto is identified by the same numeral.

In addition to the perforations 2 in fields 5 to 9, I may provide one or more pairs of perforations 10, preferably at one end of the two rows described, and in a field 11 adjoining one of the end fields 5 or 9. In Fig. 1 said perforations are in a field adjoining end field 9. The perforations in such field 11 are preferably in alignment with the perforations in the two rows and the perforations of each pair are in alignment in direction at right angles to edge 3. There may be any desired number of openings in field 11, but all that is required for my particular purpose is a number equal to one less than the number of fields such as fields 5 to 9. Therefore in Fig. 1 there are four openings 10 in field 11, and these are numbered 1, 2, 3, 4 with the perforations nearest edge 3, from left to right, being identified by numerals 1, 3, and the perforation in the second row from right to left being identified by numerals 2, 4. Whether these perforations identifying numerals in field 11 or the numerals identifying the perforations in fields 5 to 9 are arranged to read from left to right or from right to left is immaterial.

Figs. 2, 3 are merely illustrative of the manner in which the perforations are notched in each field to refer to classifications from the numeral "one" to "nine," inclusive, hence each field illustrated may be any one of the fields 5 to 9.

In Fig. 2 from left to right, the respective fields generally designated 15 that correspond to any of the fields 5 to 9, are notched to refer to classifications 3, 5, 6, 8 and 9. In Fig. 3 from left to right, the fields generally designated 16, that correspond to any of the fields 5 to 9, are notched to refer to classifications 7, 4, 2, 1. These latter numerals I will call "prime" numerals, since they correspond with the numerals that identify both rows of openings 2 in each field.

The highly important feature to note with respect to the patterns of notches produced in Figs. 2, 3 refer to the classifications 3, 5, 6, 8 and 9, which are combinations of pairs of the numerals 7, 4, 2, 1 that identify the perforations in each field, is that each pair of notches extends only to perforations in the first row, and in no instance does any of these extend to the second row. However, the pattern required to refer to classifications of the prime numbers 7, 4, 2, 1 is a single notch in any one field extending

past the perforations in the first row to a perforation in the second row.

Inasmuch as only one classification for each field is possible, it will be seen that the notch pattern for any one of the fields 5 to 9 will either extend to a pair of openings in the first row, or to a single opening in the second row, but no one field will have a combination of both.

In actual practice, for sequence sorting one 10 of the conventional sorting pins, needles, or the like (not shown) as indicated in United States Letters Patent to Rembold, No. 2,198,127, April 23, 1940, is used. By inserting such pin successively in the perforations of the first row, a

15 sequence sorting is accomplished as is done in the various patents to Perkins and Nevin hereinbefore noted. However, by using a pair of such pins in the first row for a common number, such as for 3, 5, 6, 8, 9 or a single pin in the second row for a prime number 7, 4, 2 or 1, a direct or selective sorting is possible.

In Fig. 5 for example, the card 1 is notched in field 5 for classification number "4." Field 6 is notched for number "1," field 7 for "6," field 25 8 for "7" and field 9 for "2." By insertion of a single pin in the successive perforations of the first row and lifting the pin after each insertion, the cards that drop will be in their proper order in sequence. No manipulation of the pin or pins in the second row of perforations is necessary for sequence sorting.

The card 1 of Fig. 5 as notched, refers to card number 27,614. By inserting a pin in each of the openings simultaneously in a stack of 35 cards that correspond with those notched out in the card of Fig. 5, and lifting the stack by said pins, the card of Fig. 5 and that one only (if it is the only card numbered "27,614"), will be extracted or dropped, thus accomplishing 40 a direct or selective sorting.

The use of the perforations in field 11 is only where zeroes might occur in any number, such as in the card of Fig. 4 that is card No. "90,731." There being only one zero in said number, the 45 perforation numbered "1" is slotted out. In the event the card has less than five digits, say only one, such as the numeral "1," then the perforation in the second row of field 5 (as indicated in Fig. 4) is the only one that is slotted out in 50 the fields 5 to 9, but the perforation numbered "4" in field 11 would be slotted out to indicate that the perforations in the four fields 6, 7, 8 and 9 are not slotted. A pin would, of course, be used in the openings in the stack corresponding 55 with the opening designated "1" in field 11 for direct sorting of the card of Fig. 4 or card No. 90,731.

Having described the invention, I claim:

1. A stack of cards for classification purposes, 60 each card provided with a pair of parallel rows of coded openings adjacent one edge thereof and parallel with said edge, marks dividing said rows into groups of eight openings only arranged in pairs of adjacent openings in said pair of rows, 65 patterns of notches in the edges of the cards in said stack extending to the openings in different rows in different of said groups referring to different classifications, the said notches in any one of said groups being extended to one or more 70 openings of one only of said rows, the pairs of openings in each group being identified by four different single numerals above zero that are adapted to be added in pairs to produce sums representing five of the single numerals in the 75 series of from one to nine that are not identi-

fied by said four single numerals, an additional group of openings formed in said card identified by numbers other than zero in series of progressively increasing value, the number of openings in said additional group so identified being equal to the number of said groups of eight less one, and a single notch terminating in one only of said openings in said additional group in any card bearing a classification containing one or more zeros, said openings in said additional group being arranged in pairs corresponding with the arrangement of the openings in said groups of eight.

2. A stack of cards for classification purposes, said cards bearing different classification numbers, each card being formed with a pair of parallel rows of openings parallel with and adjacent one edge thereof, marks dividing said rows into a predetermined number of groups of eight openings only arranged in four pair of adjacent openings with each pair in alignment perpendicular to said one edge, said four pair of openings, in each of said groups being identified by the numerals 1, 4, 2, 1, an additional group of openings arranged in alignment with said rows the number of which is at least equal to the number of said predetermined groups less one and no more than the number of said predetermined groups, the openings in said additional group being arranged in pairs corresponding to the arrangement of the pairs in said predetermined groups up to the nearest even number of said predetermined groups, patterns of notches in the said edges of said cards adjacent said rows extending to openings in different rows in different of said predetermined groups, the said notches in any one of said predetermined groups being extended to one or more openings of one only of said rows, and a single notch terminating in one only of the openings in said additional group in any card bearing a classification number containing one or more zeros.

3. A stack of cards for classification purposes said cards bearing different classification numbers, each card being formed with a pair of par-

allel rows of openings parallel with and adjacent one edge thereof, the openings in said rows being arranged in pairs with the openings of each pair in alignment perpendicular to said one edge, spaced marks extending perpendicular to said one edge dividing the openings in said rows into a predetermined number of groups of four of said pairs only and into one group having not less than the number of openings equal to the number of said predetermined groups less one and not more than the number of said predetermined groups, said four pair of openings in said predetermined groups being identified by the numerals 1, 4, 2, 1, patterns of notches in the said edges of said cards adjacent said rows extending to openings in each of said rows in different of said predetermined number of groups with the notches in any one of said predetermined number of groups terminating at one or more openings of one only of said rows whereby the depth of any notches in any one group will be equal, a notch extending from said edge terminating at its inner end at a certain single opening in said one group in certain of said cards in which the classification number thereof has one or more zeros.
